UNITED STATES PATENT OFFICE.

FINLAY R. MCQUEEN, OF MINNEAPOLIS, MINNESOTA.

MEANS FOR RAISING CONCRETE-MOLDS.

1,119,851.

Specification of Letters Patent.

Patented Dec. 8, 1914.

Application filed February 17, 1913. Serial No. 748,957.

To all whom it may concern:

Be it known that I, FINLAY R. MCQUEEN, a citizen of the United States, resident of Minneapolis, Hennepin county, Minnesota, have invented certain new and useful Improvements in Means for Raising Concrete-Molds, of which the following is a specification.

My invention relates to mold-raising means adapted particularly for use in building an upright concrete wall and the object of the invention is to provide a device for raising the mold which may be applied to a reinforcing rod of the concrete wall without 10 danger of buckling or bending the rod in the operation of lifting the mold.

A further object is to provide a mold-lifting means of simple, economical construction and one which can be easily operated 15 and maintained.

The invention consists generally in various constructions and combinations, all as hereinafter described and particularly pointed out in the claims.

In the accompanying drawings forming part of this specification, Figure 1 is a vertical sectional view through a portion of a mold, showing my improved lifting means applied thereto, Fig. 2 is a vertical sectional 25 view on the line $z-z$ of Fig. 1, Fig. 3 is a detail sectional view, showing the construction of the lifting mechanism, Fig. 4 is a horizontal sectional view on the line $y-y$ of Fig. 2.

In the drawing, 2 represents the mold for the concrete wall, adapted to be moved vertically as the concrete is poured and becomes set to adapt the mold for forming a concrete wall of any desired height.

3 represents a frame mounted on said mold and provided at the top with cross bars 4 wherein the upper portion of the lifting mechanism is supported, as will hereinafter appear. Suitable cross bars 5 are provided 45 near the middle of the frame 3. Between the cross bars 4 and 5 I arrange upright parallel rods 6.

7 is a reinforcing rod embedded in the concrete and extending above the same and 50 8 is a hollow screw adapted to slide on the rod 7 and secured at its lower end to angle cross bars 9 which are secured together and are slidable on the rods 6, which form guides therefor. Any suitable means may 55 be employed for securing the bars 9 and the hollow screw together, but I prefer to pro-

vide angle plates 9' having their horizontal flanges bolted to the corresponding flanges of the angle bars 9, while the vertical flanges of the plates 9' are seated against the lower end of the screw and are locked thereon by means of bolts 9'' seated within recesses 10' in said screw. The outer ends of the angle bars 9 are preferably connected with the screw by suitable braces 10''. The guide rods 6 extend preferably in staggered relation with respect to the bars 9, one of them passing through a hole at one end of a bar and the other guide rod passing through a similar hole at the opposite end of the other bar. Thus two rods serve to guide the screw vertically and prevent racking and twisting of the lower portion of the same and the clamping jaws carried thereby.

Upon the cross bars 4 blocks 10 are mounted in which the two sections of a ring 11 are seated, and adapted to enter an annular recess 12 in a nut 13 and form a thrust bearing therefor, the lower end of the nut projecting into a recess 14 in the blocks 10. This nut is mounted on the screw 8 and has a socket 15 to receive an operating handle, and when the nut is revolved the screw will be moved up or down on the reinforcing rod 7.

For the purpose of locking the screw on the reinforcing rod and moving the mold frame I provide a stationary jaw 16 mounted preferably between the angle bars 9 and having a curved toothed face 17 to bear on the surface of the rod 7. On the other side of the rod a rotating jaw 18 is eccentrically pivoted and provided with teeth 19 which bear on the reinforcing rod and clamp it securely against the jaw 16. The jaw 18 is preferably provided with a handle 20 for convenience in operating the jaw. The engagement of the jaws with the rod 7 will have a crushing stress thereon rather than one which would tend to bend or buckle the rod, and at the same time the jaws having broad bearing faces on the reinforcing rod will grip it firmly and sustain any weight which the mold frame may impose thereon.

In the operation of the device, the nut 13 is revolved and the jaw 18 will be rotated until the screw is locked on the rod 7, and continued movement of the nut 13 will lift the mold frame until the desired adjustment has been obtained. The mold may then be filled with a plastic mixture and upon reversing the movement of the nut 13

the eccentric jaw will be disengaged from the reinforcing rod and the screw moved upwardly on the guide axis a suitable distance, ready for another lifting movement. 3 In case the jaw 18 should stick or bind at any time, the insulite 20 may be utilized for releasing it.

I have found that this apparatus is capable of sustaining an extremely heavy load, 10 that the clamping jaws will not bend or buckle the reinforcing rod, and that the apparatus can be easily and quickly adjusted in its lifting position.

I claim as my invention--

15 1. The combination, with a mold frame, of a reinforcing rod, a hollow screw arranged to slide on said rod, means holding said screw against rotary movement, a stationary jaw carried by said screw and having 20 a toothed face adapted to engage one side of said rod, a rotating, eccentrically mounted jaw also having a toothed face arranged to engage the other side of said rod, a rotatable nut mounted on said frame and 25 engaging said screw, the revolution of said nut in one direction operating to set said eccentric jaw in its clamping position and lift said frame, and the revolution of said nut in the opposite direction operating to 30 release said jaw and raise said screw and jaws.

2. The combination, with a mold frame, of a reinforcing rod, a screw mounted to slide on said rod, bars secured to the lower 35 end of said screw and extending transversely thereof, guide rods mounted in said frame and wherein said bars are vertically slidable, whereby said screw is held against rotary movement, a stationary jaw secured 40 to said bars and having a clamping face to contact with one side of said rod and a movable jaw also secured to said bars and having a face to contact with the opposite side

of said rod, and a rotatable nut mounted on 45 said frame and engaging the threads of said screw, the revolution of said nut in one direction locking said jaws on said rod to lift said frame and its revolution in the other direction releasing said jaws to lift them and said screw.

3. The combination, with a mold frame, of a reinforcing rod, a jaw frame having guides in said mold frame, whereby said jaw frame is permitted to move vertically, but is held against rotary movement, a stationary jaw mounted in said jaw frame and having a broad bearing face to engage said rod, a movable jaw eccentrically pivoted in said jaw frame and having a face to engage said rod and clamp it against said stationary jaw with a crushing stress, and means for exerting a downward pressure on said jaw frame to set said jaws on said rod and lift said mold frame, or an upward pull to release said jaws from said rod and lift 65 them and their frame on said rod.

4. The combination, with a frame, of a reinforcing rod, a hollow member mounted to slide on said rod, means holding said member against rotary movement, means 70 engaging said hollow member and having a thrust bearing on said frame, jaws carried by said member upon opposite sides of said rod, one of said jaws being stationary and having a face to fit the surface of said rod, 75 the other jaw being eccentrically mounted and having a rotating movement for clamping said rod between its face and the face of said stationary jaw, substantially as described.

In witness whereof, I have hereunto set my hand this 12th day of February, 1913.

FINLAY R. MCQUEEN.
